UNITED STATES PATENT OFFICE.

MAXMILIAN ERNST, OF CLEVELAND, OHIO.

DESIGN FOR A BADGE.

SPECIFICATION forming part of Design No. 24,352, dated June 4, 1895.

Application filed May 7, 1895. Serial No. 548,446. Term of patent 3½ years.

To all whom it may concern:

Be it known that I, MAXMILIAN ERNST, a citizen of the United States of America, residing at Cleveland, in the county of Cuyahoga and State of Ohio, have invented and produced a new and original Design for Badges, of which the following is a specification, reference being had to the accompanying drawing, forming a part thereof.

10 The drawing shows a face view of a badge embodying my design.

The leading features of my design consist in the representation or grouping of a figure representing an unfurled flag; another figure representing a wreath mounted upon the flag 15 at the central portion of the badge, and another figure representing a bird and arranged at the top of the badge.

What I claim is—

The design for a badge, herein shown and 20 described.

In testimony whereof I sign this specification, in the presence of two witnesses, this 23d day of March, 1895.

MAXMILIAN ERNST.
